UNITED STATES PATENT OFFICE.

JOHN M. KROYER, OF STOCKTON, CALIFORNIA, ASSIGNOR TO SAMSON SIEVE-GRIP TRACTOR CO., OF STOCKTON, CALIFORNIA, A CORPORATION OF CALIFORNIA.

TRACTOR-WHEEL.

1,283,915.

Specification of Letters Patent. Patented Oct. 29, 1918.

Application filed March 31, 1917. Serial No. 158,850.

To all whom it may concern:

Be it known that I, JOHN M. KROYER, a citizen of the United States, and a resident of Stockton, county of San Joaquin, State of California, have invented certain new and useful Improvements in Tractor-Wheels, of which the following is a specification.

This invention relates to improvements in wheels particularly designed for use as the propelling and other wheels for tractors.

One of the objects of my invention is to produce a wheel which is comparatively light and inexpensive to manufacture inasmuch as it is integral in structure, and therefore requires no assembling of parts, thereby decreasing the cost of labor and material. Another object is to so construct a tractor wheel as to render unnecessary the use of precautions against miring and slipping. Another object is to so construct and arrange the angle grips as to render sure the support for the tractor wherever it may be used. Another object is to so construct and arrange the angle grips on the periphery of the wheel as to not only prevent the packing of the soil, but on the contrary to loosen and stir the surface of the soil by the action of the grips, and also to effectively crush or break clods.

Another object of my invention is to so construct the wheel as to render it suitable for machines of various sizes and weights. Another object is to provide in combination with a skeleton tractor wheel a road band for use when running the machine over asphalt, macadam or other roads, the band being so constructed as to be easily removed from or attached to the wheel. Another object is to provide a center drive for the tractor wheel. Other objects will appear from the following description and claims.

Referring to the drawings in which the same reference character indicates the same part in the several views:

Figure 1 is a perspective view of one embodiment of my improved tractor wheel.

Fig. 2 is a plan view of the periphery of the wheel, broken away showing the cutter rings and angle grips.

Fig. 3 is a section on line 3—3 of Fig. 2.

Fig. 4 is a perspective of a modified construction of my improved tractor wheel showing the road band in place.

Fig. 5 is a horizontal section on line 5—5 of Fig. 4.

In the drawings the wheel W is of metal preferably cast in a single structure. The casting has a skeleton formation, and it consists essentially of a hub 10, spokes 11, cutter ring 12 directly secured to the spokes, a cutter ring 13 of the same diameter as the cutter ring 12 and secured thereto by means of angle grips 14 and 15, the inner end of said angle grips being secured alternately to a central ring 16, which central ring is of slightly less diameter than that of the cutter rings heretofore referred to.

In the construction shown in Fig. 1, the diameter of a circle drawn from the center of the wheel with the inner central corner 70 of the upright flange of the angle grips as a radius, is substantially the same diameter as the periphery of the side cutter rings. The outer corners of the upright flanges of the angle grips extend a short distance above the 75 peripheries of the cutter rings.

Each of the angle grips is substantially L-shaped, the ends of each alternate grip extending from and at an angle to the cutter rings, the other ends of the angle grips 80 alternately meeting with and being secured to the central ring also at an angle thereto as shown.

In order to prevent the packing of dirt and material from the soil over which the 85 tractor is moved, the cutting rings 12 and 13, the peripheries of each of which are formed with a suitable cutting edge at 12' and 13', are cut away respectively at the points 18 and 19 adjacent the upright flanges 90 of the angle grips so as to allow for the free movement of the dirt longitudinally past each grip as the forward or free end of the grip impinges upon the soil and the wheel is turned to carry the tractor and pull its 95 load.

A circular rack 20 formed with teeth 21 on its inner surface is secured by bolts 22 to the central ring 16, for the purpose of providing a true center drive for the trac- 100

tor wheel, this driving gear being engaged by a pinion secured to a shaft which is turned by the engine of the tractor.

Figs. 4 and 5 show the removable road band 30 which may be secured to the tractor wheel in any suitable manner, preferably by bolts 31, the heads of which are substantially flush with the surface of the road band, and the ends are secured in any suitable manner by nuts 32 to any suitable part of the wheel, preferably the horizontal flanges 33 of the angle grips, as shown.

As shown in Figs. 4 and 5 a wheel may be constructed in which the upright flanges 34 of the angle grips will extend a substantial distance above the cutter rings. By "substantial" I mean that the flange extends above the periphery of the cutter rings a distance two-thirds or three quarters of its height. This construction is especially useful when the machine is to operate on loose sandy soil.

By means of the above described construction, I have found that tractor wheels do not pack the soil, but on the contrary stir up the surface of the soil, thereby rendering assistance toward preparing the soil for planting or seeding.

Tractor wheels constructed in accordance with my invention render equally good and efficient traction when they are used over or upon either soft soil formation, sandy soil recently plowed or cultivated orchards or fields. They are also very useful as clod crushers or clod breakers, and therefore, they are useful in pulverizing the more or less solid and extended clods which are often formed by the plow and left upon a field after plowing.

I have found that this clod crushing is much more effectively accomplished by the use of my invention than by the ordinary implements heretofore in use for that purpose.

While, of course, dimensions in inches are not the essence of my invention, yet to illustrate the relative dimensions and diameters, the following figures are given: In a wheel in which the outer peripheries of the cutter rings are in circles having diameters of 40 inches, and the outer periphery of the center ring is in a circle having a diameter of 39 inches, the inner free corners of the upright flanges lie in a circle having a diameter of 40 inches, and the outer free corners of the upright flanges of the angle grips on each side of the wheel lie in circles having diameters of 41 inches.

My invention is not limited to the driving wheels of the tractor, but is also used in the construction of the front or guiding wheels, and therefore the construction illustrated and described is the same for the front or

guiding wheels as it is for the driving wheel, except of course, that the circular rack is not attached to the central ring on a front or guiding wheel.

It is to be understood that the drawings and the above description are merely illustrative and that the invention is not to be limited in any respect except as defined in the subjoined claims.

Having now described my invention, what I claim as new and desire to secure by Letters Patent is:

1. A tractor wheel having a hub, spokes integrally formed with the hub at one side of the wheel, a cutter ring in the plane of and integrally formed with the spokes, and another cutter ring at the opposite side of the circumference of the wheel integrally formed with the first cutter ring but otherwise disconnected from the spokes.

2. A tractor wheel having a hub, spokes integrally formed with the hub at one side of the wheel, a cutter ring in the plane of and integrally formed with the spokes, a second cutter ring at the opposite side of the circumference of the wheel, and obliquely arranged grips formed integrally with the cutter rings.

3. A tractor wheel having a hub, spokes integrally formed with the hub at one side of the wheel, a cutter ring in the plane of and integrally formed with the spokes, a second cutter ring at the opposite side of the circumference of the wheel, an intermediate ring, and a series of grips extending obliquely from the cutter rings and formed integrally with the cutter rings and intermediate ring.

4. A tractor wheel comprising cutter rings at opposite sides thereof, a ring intermediate the cutter rings, and two series of grips, one series of said grips extending obliquely in one direction from one cutter ring to the intermediate ring, and the other series of grips extending obliquely in the opposite direction from the other cutter ring to said intermediate ring, said rings and grips being formed integral with each other.

5. In a skeleton tractor wheel, a hub, cutter rings integrally secured to the hub, a center ring, and substantially L-shaped angle grips, the horizontal flange of each angle grip being secured to a cutter ring and to the center ring, and the upright flange of each angle grip being secured to a cutter ring.

6. In a tractor wheel, cutter rings, a ring disposed midway between the cutter rings, and substantially L-shaped angle grips alternately projecting inwardly from each cutter ring to the center ring and disposed at an oblique angle to each of said rings.

7. A tractor wheel provided with cutter rings at each edge of the circumference, an

intermediate ring and a series of parallel grips extending obliquely from one cutter ring and a like series of parallel grips extending obliquely from the other cutter ring, 5 the grips of the two series being arranged in staggered relation with each other and terminating serially at the intermediate ring.

8. A tractor wheel comprising cutter rings on each edge of the circumference thereof, 10 a ring intermediate the cutter rings, and grips formed integrally with the rings extending from each cutter ring to the intermediate ring, the outer edges of the grips at the intermediate ring being of less radial 15 height than the cutter rings and inclined until they project radially beyond the cutter rings.

9. A tractor wheel comprising cutter rings on each edge of the circumference thereof, a 20 ring intermediate the cutter rings, and grips formed integrally with the rings extending obliquely from each cutter ring to the intermediate ring, the outer edges of the grips at the intermediate ring being of less radial 25 height than the cutter rings and inclined until they project radially beyond the cutter rings.

10. A skeleton tractor wheel consisting of a hub, spokes, cutter rings, a ring midway 30 between the cutter rings and angle grips integrally connected thereto and an internal gear ring or circular rack removably secured to said center ring.

11. A tractor wheel provided with side 35 cutter rings, a ring substantially midway be-

tween the cutter rings, a series of grips connecting the intermediate ring with each cutter ring, and a band extending around the wheel removably secured to and covering said grips.

40

12. A tractor wheel provided with side rings, a ring substantially midway between the side rings, grips connecting the intermediate ring with each side ring and formed to provide outer edges and base flanges, and 45 a band covering the outer edges of the grips and detachably secured to the base flanges of the latter.

13. A tractor wheel having a pair of side rings having peripheral cutting edges, a ring disposed substantially midway between the side rings and angle grips alternately projecting inwardly from each side ring to the center ring and disposed at an angle to each of said rings.

14. A tractor wheel comprising a pair of side cutter rings having openings in their edges, a ring substantially midway between the cutter rings, and a series of grips formed integral with the cutter rings and intermediate ring and having their outer ends adjacent to the openings in the cutter rings.

Signed at the borough of Manhattan, city and State of New York, this 15th day of March, 1917.

JOHN M. KROYER.
